UNITED STATES PATENT OFFICE.

JOSEPH TRISKA, OF OMAHA, NEBRASKA.

RADIATOR.

Application filed February 1, 1923. Serial No. 616,349.

My invention relates to the construction of radiators of the class employed for water-cooled internal-combustion engines. It is the object of my invention to provide a radiator of this class, so constructed that should the water therein be frozen, immediately upon starting the engine the radiator will be thawed sufficiently to open a passage through which circulation of the water 5 may occur through the radiator to and from the engine. This object of my invention, namely, the provision of a self-thawing radiator, entirely automatic in action and requiring no attention or regulation, is attained by a relatively slight modification of the construction usually employed in radiators for motor vehicles and the like.

In the accompanying drawings Fig. 1 is a front view of a radiator constructed in accordance with my invention, Fig. 2 is a transverse section of the same on the line 2—2 of Fig. 1, and Fig. 3 is a detail bottom view of the same.

In the illustrated construction the main portion of the radiator is of ordinary and well-known structure, there being an outer frame-portion 4, an upper tank or header 5 provided at its rear side with the inlet-pipe 6 and at the top having the filling-neck 7 carrying the removable cap 8, a lower tank 9 having connected therewith the outlet-pipe 10, vertical tubes 11 connecting the tanks 5 and 9, and radiating plates or flanges 12 extending horizontally across the spaces between the tubes 11. Instead of the tubes 11 and plates 12, the radiator proper, or heat-dissipating structure between the upper and lower tanks may be of the cellular or other common type, the essentials being the provision of thin-walled passages for the flow of water from the upper to the lower tank, the water-passages being interspersed with horizontal passages for the flow of air to carry off the heat radiated from the water passages. In the usual structure of radiators of this class, there is an overflow-pipe arranged so that the upper end thereof opens within the filling-neck, the pipe being extended through the rear side of the upper tank and thence downwardly, and forming a passage for the escape of excess of water from the tank, or for the escape of steam therefrom. In my improved construction, the overflow-pipe 13 has the open upper end thereof arranged in the filling-neck 7 in

the usual way, but is extended downwardly through the upper tank 5, instead of being carried out through the rear side of said tank. From the lower portion of the tank 5 the pipe 13 is extended directly downward through the body of the radiator proper, in the illustrated structure said pipe taking the place of one of the water-circulating tubes 11, and extending through the lower tank 9 adjacent to the outlet-pipe 10. Emerging from the lower tank, the overflow pipe is turned rearwardly alongside the outlet-pipe, and terminates adjacent thereto, being directed as shown in Fig. 3 so that steam emerging therefrom will impinge upon the side of said pipe 10.

Freezing of the water in the engine-cooling system of a motor vehicle is most likely to occur in the lower portion of the radiator, then in the lower tank and outlet-pipe, and lastly in the upper portion of the radiator, the upper tank, inlet-pipe, and within the water-jackets of the engine itself. It is customary during the winter season to fill the radiators of automobiles with alcoholic or other so-called "non-freezing" mixtures, but in extremely cold weather such mixtures are apt to become partially frozen into a slushy mass which will not circulate through the radiator. When the engine is started, after freezing of the water or other liquid mixture in the cooling system, circulation is prevented and as a result thereof the liquid in the cylinder-jackets and in the pipe leading therefrom to the upper tank of the radiator is quickly heated to boiling temperature, and the steam therefrom rises into the filling-neck and passes out through the overflow-pipe. Ordinarily, the heat from the steam so produced will only cause thawing of the lower portion of the radiator after the lapse of a considerable time, during which overheating and serious injury of the engine may result, as the engine-cylinders will not be efficiently cooled until the thawing has proceeded far enough to enable the water-circulation to be re-established.

With my improved radiator construction, when the water circulation becomes stopped by freezing, and steam is produced as above described, the steam escaping through the pipe 13 will quickly thaw those portions of the radiator contiguous to said pipe, and through which the same passes, including the portion of the lower tank adjacent to

the outlet-pipe 10, while the escaping steam from the end of the pipe 13 will impinge upon the side of the pipe 10 to quickly thaw any liquid frozen therein. It will be seen that thus a passage will be opened through the radiator, completing a circuit from and to the engine, through which the water-circulation will at once be re-established, even though the side-portions of the radiator, which are remote from the pipe 13, remain frozen. With the commencement of water-circulation, through any portion of the radiator, all danger of injury to the engine, by inefficient cooling of the cylinders, is past, and it is found in practice that the thawing of the remaining frozen portions of the radiator will proceed very rapidly after the water circulation has been started through any portion thereof.

Under ordinary or normal conditions, the overflow-pipe 13 as arranged in accordance with my invention will function in the usual way, draining off any excess of water when the level in the upper tank rises above the end of said pipe within the filling-neck, and permitting the escape of steam should the temperature of the water become high enough to cause its formation.

Thus, by the mere extension of the overflow-pipe through the radiator itself, parallelling the direction of water-circulation from the inlet to the outlet pipes thereof, the radiator is automatically caused to be thawed promptly following the starting of the engine; and the structure by which the thawing is effected requires no attention.

by the user, and involves a very moderate expense for its construction.

Now, having described my invention, what I claim and desire to secure by Letters Patent is:

1. The combination with a radiator of the class described, of an overflow-pipe arranged to receive steam from the uppermost chamber of the radiator, said pipe extending downwardly through the body of the radiator adjacent to continuous water-passages therein, and through the lower chamber adjacent to the outlet therefrom, and having its lower end directed to discharge impinging upon the outlet-pipe from said lower chamber, for the purpose set forth.

2. In a radiator of the class described, the combination with upper and lower tanks, inlet and outlet pipes connecting respectively with said tanks, and a connecting body between said tanks having multiple passages for the flow of liquid from one to the other; of an overflow-pipe starting in the upper portion of the upper tank, thence descending through said tank, through the connecting body, thence through the lower tank at a portion thereof adjoining the outlet pipe, and thence directed to discharge impinging upon the outlet pipe whereby a flow of steam through said overflow-pipe may serve to thaw frozen liquid in and thereby open a continuous passage through the radiator between the inlet and outlet pipes thereof.

JOSEPH TRISKA
